T. R. E. RUNDQVIST

DRILLING MECHANISM

Filed March 13, 1924

UNITED STATES PATENT OFFICE.

THORE R. E. RUNDQVIST, OF CLAREMONT, NEW HAMPSHIRE, ASSIGNOR TO SULLIVAN MACHINERY COMPANY, A CORPORATION OF MASSACHUSETTS.

DRILLING MECHANISM.

Application filed March 13, 1924. Serial No. 699,112.

This invention relates to drilling mechanisms.

It has for its object to provide an improved drilling mechanism. A further object is to provide an improved drilling mechanism having improved means for increasing the efficiency of the drilling motor. Another object is to provide an improved drilling mechanism having a fluid actuated feeding mechanism and means associated with said latter means for increasing the operating efficiency of the drilling motor. A further object is to provide an improved constant pressure chamber within the feeding cylinder 15 for the drilling motor.

In the accompanying drawings I have shown for purposes of illustration one form which my invention may assume in practice.

In these drawings—

Fig. 1 is a side elevation partly broken away to show details of construction.

Fig. 2 is a fragmentary side elevation of the rear end of the feed piston rod.

Fig. 3 is a transverse section taken on line 25 3—3 of Fig. 1.

Fig. 4 is an end elevation of Fig. 2.

Fig. 5 is a detail sectional view through the control valve showing the position of the several ports when the feed is reversed.

In the illustrative form of my invention I have shown the same embodied in a drifter type of drill, although it will be obvious that any other type of drill may be used, and which comprises a combined shell and feed cylinder 1 having a depending bracket 2 adapted to engage any suitable support while extending upwardly therefrom are longitudinally disposed guideways 3 within which the drilling mechanism, generally indicated at 4, is slidably mounted. More specifically, the drilling mechanism comprises a usual percussive motor cylinder 5 having a forwardly extending chuck housing 6 adapted to carry a steel 7 while a rear cylinder head 8 is fixed on the cylinder 5 as by any suitable side rod construction 9.

The feeding mechanism for my improved device comprises a rearwardly extending hollow arm 10, herein shown as having a hollow portion 11 of considerable size, while formed in the upper and lower sides thereof are longitudinal passages 12 and 13 respectively. The arm 10 is disposed within a conical bore 14 formed in the hollow portion 55 of the head 8 and held therein as by a

threaded connection 15 adjacent the rear side of a vertical passage 16 which allows communication between the hollow portion 11 and a main supply passage 17 leading to the drilling motor from a main control valve 18. The upper passage 12 has communication with an upwardly extending passage 19 adapted to be vented to atmosphere when the valve 18 is in the position shown in Fig. 1 as by a groove 20 formed in the periphery 60 of said valve. The lower passage 13 communicates with a source of live pressure fluid in the valve 18 as by an annular groove 21 formed in the forward reduced portion 65 of the member 10 which communicates with a passage 22, groove 23 and port 24 leading 70 to the interior of the valve 18, from which live pressure fluid will flow. Projecting downwardly from the rear end of the member 10 is a member 25 having an annular recess 26 within which the member 10 seats 75 and held therein by screws 27 threaded into lugs 28 formed on the member 10. The lower portion of said member 25 has a second annular recess 29 within which the rear end 80 of a hollow feed piston rod 30 is disposed and held therein by screws 31 threaded into lugs 32 formed on, or welded to, the piston rod. The piston rod projects forwardly through a combined rear cylinder head and 85 packing member 33 and carries at its forward end a piston 34, the front head of the cylinder 1 being closed by head 35. The hollow portion 11 in the member 10 has communication with the hollow portions 36 and 37 formed in the end of the member 25 and 90 piston rod 30, respectively. These hollow portions form a closed chamber within which live fluid pressure is admitted only through the passage 16 and has such a capacity that 95 pressure fluctuations in the fluid conducting passage 17 will be reduced to a minimum, the pressure fluctuations being reduced due to the fact that the pressure of the fluid within the hollow portions acts as a constant pressure chamber. It will thus be seen that I 100 have taken advantage of already existing and necessary structure in a drilling mechanism to provide a suitable constant pressure chamber in which an additional source 105 of pressure fluid may be stored. By my improved arrangement excessively large additional storage chambers are not required, thus keeping the weight of my device down to a minimum.

The means for feeding my device in combination with this improved constant pressure chamber means comprises passages 40 and 41 formed in the end member 25 which 5 allow communication between the passages 12 and 13 and passages 42 and 43, respectively, formed in the piston rod 30. The passage 43 communicates with the rear side of the piston 34 as by a port 44 while the 10 passage 42 communicates with the front side of the piston as by a port 45 formed in the front end of the piston 34. It is to be noted that live pressure fluid will be supplied to the rear side of the piston 34 when the main 15 control valve 18 is in the position shown in Fig. 1, at which time the front side of said piston will be vented to the atmosphere. If, however, it is desired to reverse the direction of feed, the valve 18 may be rotated to vent 20 the cylinder on the rear side of said feed piston while admitting live pressure fluid to the front side thereof.

While I have in this application specifically described one form which my invention 25 may assume in practice, it will be understood that this form of the same is shown for purposes of illustration and that the invention may be modified and embodied in various other forms without departing 30 from its spirit or the scope of the appended claims.

What I claim as new and desire to secure by Letters Patent is:

1. In a drilling mechanism comprising a 35 fluid actuated drilling motor, a fluid actuated feeding means therefor including a piston, an angular connection between said motor and a portion of said feeding means, means for controlling fluid flow to said motor 40 including a fluid supply passage, and a constant pressure chamber for diminishing motor inlet pressure fluctuations formed in said angular connection and communicating with said fluid supply passage.
- 45 2. In a drilling mechanism comprising a fluid actuated drilling motor, a fluid actuated feeding means therefor including a piston, and means for controlling fluid flow to said motor including a motor inlet passage 50 extending between the source of fluid supply and said motor, and a laterally located constant pressure chamber for diminishing motor inlet pressure fluctuations commun-

cating with said motor inlet passage between its ends and formed in part within said piston.

3. In a drilling mechanism comprising a fluid actuated drilling motor, feeding means therefor including a feed piston and an angular tubular connection between said motor 60 and feed piston, means for controlling fluid flow to said motor and feeding means comprising a motor inlet passage, and a constant pressure chamber for diminishing motor inlet pressure fluctuations comprised 65 in said angular tubular connection and communicating with said motor inlet passage.

4. In a drilling mechanism comprising a fluid actuated drilling motor, feeding means therefor comprising a piston and a tubular 70 piston rod, means for controlling fluid flow to said motor including a motor inlet passage extending between the source of fluid supply and said motor, and a constant pressure chamber for diminishing motor inlet 75 pressure fluctuations formed in said piston rod and having a lateral branch passage communicating with said motor inlet passage.

5. In a drilling mechanism comprising a 80 fluid actuated drilling motor, feeding means therefor including a rearwardly extending hollow arm secured to said motor, a tubular piston rod secured to the feed piston, and a detachable hollow member connecting said arm and rod, means for controlling fluid flow to said motor including a fluid supply passage, said arm, connecting member, and rod forming a constant pressure chamber for diminishing motor inlet pressure fluctuations and having a passage communicating 85 with said fluid supply passage.

6. In a drilling mechanism comprising a fluid actuated drilling motor, feeding means therefor including a tubular feed piston rod having a parallel return bend portion forming a continuation thereof, a feed piston carried thereby, and means for controlling fluid flow to said motor including a fluid supply passage, said piston rod and return bend forming a constant pressure chamber for diminishing motor inlet pressure fluctuations communicating with said fluid supply passage.

In testimony whereof I affix my signature.

THORE R. E. RUNDQVIST.
